UNITED STATES PATENT OFFICE

109,659

DESIGN FOR A SPREAD OR SIMILAR ARTICLE

Marie F. Hauck, Chicago, Ill., assignor to Walter
M. Gotsch Company, Chicago, Ill., a corporation of Illinois

Application April 4, 1938, Serial No. 76,282

Term of patent 3½ years

To all whom it may concern:

Be it known that I, Marie F. Hauck, a citizen of the United States, residing at Chicago, in the county of Cook and State of Illinois, have invented a new, original, and ornamental Design for a Spread or Similar Article, of which the following is a specification, reference being had to the accompanying drawing, forming part thereof.

In the drawing.

Fig. 1 is a plan view of a spread or similar article, illustrating my new design; and

Fig. 2 is an enlarged detail of a portion of the pattern illustrating the tufting.

I claim:

The ornamental design for a spread or similar article, as shown.

MARIE F. HAUCK.
